UNITED STATES PATENT OFFICE.

CHARLES T. WITTSTEIN, OF NEWARK, NEW JERSEY, ASSIGNOR TO ARCH CROWN MFG. CO., A CORPORATION OF NEW JERSEY.

GEM SETTING.

Application filed November 12, 1919. Serial No. 337,479.

To all whom it may concern:

Be it known that I, CHARLES T. WITTSTEIN, a citizen of the United States, and a resident of Newark, in the county of Essex and State of New Jersey, have invented new and useful Improvements in Gem Settings, of which the following is a specification.

This invention relates in general to gem settings, and more particularly to a setting for the more precious gems, such as diamonds.

The objects of the invention are to provide a setting or mounting of this character embodying novel features of construction whereby the setting appears from casual observation to be a part of the stone or gem so that the stone appears larger, and the setting so blends therewith that the stone and setting appear to be one stone; to provide such a setting which enhances the lustre of the stone; to provide a setting comprising a faceted bezel crown adapted to be secured in a conventional skeleton or pronged setting to admit light under the gem; to construct certain of the facets of said bezel so that they serve to hold the gem within the bezel; to form the bezel with positioning means to engage the prongs of a conventional setting for mounting the bezel within the said setting; to secure a simple construction and method for mounting the gem within the bezel which in no manner detracts from the appearance of the bezel or the gem; and to obtain other objects and results as may be brought out by the following description.

Referring to the accompanying drawings, in which like numerals of reference indicate the same parts throughout the several views,

Figure 1 is a perspective view of a gem setting embodying my invention, showing the same upon a finger ring;

Figure 2 is a vertical sectional view through the same;

Figure 3 is a side elevation of the bezel and stone removed from the ring;

Figure 4 is a view similar to Figure 2 showing the setting before the bezel is fastened therein, and showing the fastening facets of the bezel before they are flattened or burnished over the stone, and

Figure 5 is a detail perspective view of the bezel as shown by Figure 4.

In the specific embodiment of the invention illustrated, the numeral 1 designates the bezel or crown which is substantially frusto-

conical and is provided with a centrally disposed gem receiving opening 2. The under side 3 of the bezel is substantially flat, and the outer edge 4 thereof is beveled inwardly to fit into a conventional gem setting. The upper side of the bezel is inclined upwardly and inwardly from the edge thereof and is formed with a plurality of series of similarly formed polygonal raised facets 5 which extend inwardly toward the opening 2, between each series of which is a pair of downwardly converging depressed facets 6 whose surfaces are disposed below the surfaces of the facets 5, as shown by Figures 3 and 5. At their outer edges the facets 6 join the adjacent facets 5, while their adjacent edges meet, as at 7, below the planes of the facets 5. The meeting points of the adjacent edges of all the facets 6 at the opening 2 are disposed in substantially a common plane, and the walls of the opening 2 incline downwardly and inwardly from these points, as at 8, to form a seat or bearing for the faceted gem or stone 9, the girdle 9^a of which when fitted in the bezel is substantially flush with the inner ends of the said meeting edges of the facets 6. The plane of the central facet 5^a of each series 5 before the stone is set intersects the edges of the opening 2 slightly above the girdle line of the stone 9 in the opening, as shown by Figures 4 and 5. When the stone is placed in the bezel the inner pointed ends 5^b of these facets 5^a are flattened or burnished over the stone as shown by Figures 2 and 3, and the stone is thus firmly held in the bezel. These points form parts of the facets 5^a and overlap the stone just sufficiently to hold it in the bezel, so that they are substantially invisible to a casual observer.

The bezel is adapted for use with many forms of settings, but for the purposes of illustration the bezel is shown as mounted in a conventional skeleton or pronged setting. When such a setting is used the peripheral edge 4 of the bezel is preferably provided with a plurality of spaced notches 4^a equal in number to the prongs 10 of a setting 11, and preferably formed in the inclined depressed facets 6. The bezel is mounted in the setting 11 with its flat underside 3 seated on shoulders 10^a formed in the prongs 10 and with the ends of the prongs engaging the notches 4^a. The ends 12 of the prongs 10 are then upset or flattened down

over the edge of the bezel and between the facets 6. The bezel is thus firmly mounted in the setting 11 and the notches 4^a prevent slipping of the bezel in the prongs, as well as providing positioning means for arranging the bezel in the prongs. The ends of the prongs engage the oppositely inclined surfaces of the facets 6 and thus also serve to prevent movement or slipping of the bezel 10 in the prongs 10.

The bezel 1 is preferably formed of a highly polished metal, such as platinum or white gold so as to be of substantially the same color as the stone, and the facets are 15 of a formation similar to the facets of the gem. It will thus be obvious that the facets 5 and 6 will reflect light and produce a lustre very similar to the stone so that the stone and bezel appear to be one stone. 20 Furthermore, substantially the whole upper surface of the stone is completely exposed by fastening it in the bezel by means of the points 5^b of the facets 5^a so that only minute portions of the stone are covered, 25 and this fastening means forming a part of the facets is substantially invisible so as not to detract from the appearance of the stone in any manner. While I have shown the bezel mounted in one conventional type of 30 setting it will be understood that it can be mounted in any desirable setting; and furthermore, the bezel is adapted for use with all jewelry settings, such as ear rings, scarf pins, etc., as well as with finger rings as 35 illustrated.

Having thus described the invention, what I claim is:

1. A crown for jewelry settings provided with a centrally disposed gem receiving 40 opening, said crown being formed with a plurality of facets, certain of said facets bordering the said opening extending inwardly over the girdle of the gem to hold the same in the opening in the crown, the inner ends of the meeting edges of others 45 of the facets bordering the said opening being flush with the girdle of the gem.

2. A crown for jewelry settings provided with a central gem receiving opening, said 50 crown being formed with a plurality of facets bordering said opening, the inner ends of certain of said facets being disposed

in a common plane above the edge of said opening while the inner ends of the meeting edges of others of said facets are arranged in the plane of the edge of said opening. 55

3. A crown for jewelry settings provided with a central gem receiving opening having downwardly beveled walls, said crown 60 being formed with a plurality of facets some of which border said opening with their inner ends arranged in a common plane above the upper edge of said opening and extending inwardly over the edge of said opening 65 to hold a gem therein, while the inner ends of the meeting edges of others of said facets are arranged flush with the said upper edge of the opening.

4. A crown for jewelry settings provided with a centrally disposed gem receiving opening; said crown being formed with a plurality of facets arranged at spaced points around said opening, the inner ends of said facets extending inwardly over the girdle 75 of the gem to hold the gem in the said opening, said crown being also formed with other facets intermediate said first-mentioned facets with the inner ends of their meeting edges flush with the girdle of the gem. 80

5. A crown for jewelry settings provided with a centrally disposed gem receiving opening, said crown being provided with a plurality of similarly formed polygonal facets arranged at spaced intervals around 85 the edge of said opening, the inner angle of each of said facets being disposed above and extending inwardly over the girdle of the gem, said crown being also formed with a pair of downwardly converging facets 90 intermediate adjacent ones of said first-mentioned facets with the inner ends of their meeting edges disposed substantially flush with the said girdle of the gem.

6. The combination with a pronged jewelry setting, of a crown portion having a plurality of pairs of downwardly converging meeting facets in the upper side thereof, and notches formed in the edges of said crown portion and intersecting said facets, said 100 notches and facets receiving the prongs of the setting to hold the crown portion in position therein. 95

CHARLES T. WITTSTEIN.
